UNITED STATES PATENT OFFICE

147,884

DESIGN FOR A CHILD'S CAR SEAT OR SIMILAR ARTICLE

Dorothy Bitter, New York, N. Y., assignor to Co-Pilot Corp., a corporation of New York

Application February 4, 1946, Serial No. 126,236

Term of patent 7 years

(Cl. D34—5)

To all whom it may concern:

Be it known that I, Dorothy Bitter, a citizen of the United States, residing in the city of New York, Borough of Manhattan, in the county of New York and State of New York, have invented a new, original, and ornamental Design for a Child's Car Seat or Similar Article, of which the following is a specification, reference being had to the accompanying drawings, constituting a part thereof.

Fig. 1 is a perspective view of a child's car seat or similar article showing my new design; and

Fig. 2 is a side elevational view thereof.

The essential features of the present design reside in the portions shown in solid lines in the drawing.

I claim:

The ornamental design for a child's car seat or similar article, substantially as shown and described.

DOROTHY BITTER.
